UNITED STATES PATENT OFFICE.

GEORGE W. PIERCE, OF CAMBRIDGE, MASSACHUSETTS, ASSIGNOR TO SUBMARINE SIGNAL COMPANY, OF PORTLAND, MAINE, A CORPORATION OF MAINE.

ELECTRIC COMPENSATOR.

Application filed June 25, 1919. Serial No. 306,689.

The present invention relates to compensation, and more particularly to electric compensators. An electric compensator is a device for introducing suitable time retardation into one or more electrical currents, in such a way that electrical disturbances set up in two or more receiving elements may be brought into combination in a useful manner. The electric compensator may be employed to determine the direction of distant sources of radiant energy, particularly sound sources. Some of the principles employed are adaptable to the determination of the direction of sources of electric waves. In addition to the determination of the direction of radiant energy sources, the compensator is adaptable also to use in focusing the receiving system on one of several radiant energy sources and thus eliminating or suppressing energy from undesired sources.

In the drawings Fig. 1 is a diagrammatical view illustrating the principle of the electric compensator as applied to two receiving units.

Fig. 2 is a diagrammatic development showing the principle of operation of the electric compensator switch, in connection with its circuits, for two receiving units.

Fig. 3 is a diagrammatic bottom plan view of the switch and connections used for two receiving units.

Fig. 4 is a cross section showing the structure of the rotary switch which is shown diagrammatically in Fig. 3.

Fig. 5 is a wiring diagram of the electric compensator and its connections for two lines of twelve receiving units each, with a development of the switch.

Fig. 6 is a diagram showing in perspective the switch disc and electrical connections for a compensator for two lines of twelve receiving units each.

For purposes of illustrating the principle of operation let us suppose that there are two receiving elements actuated by wave energy, such as sound waves, coming from some particular direction. In general this energy will strike one of the receiving elements before it strikes the other receiving element. If currents are set up in two receiving elements, the current in one element will be in advance of the current in the other element. By introducing into the advance element, suitable means for retarding the current in it, it is

possible to bring the currents in the two elements into phase. These two currents in phase may now be introduced into a translating device which will give a greater response than would be obtained if the two currents were out of phase. The amount by which the currents in the original receiving elements were out of phase will depend upon the direction of the source of wave energy with respect to a line through the two receiving elements, so that the amount of retardation that is introduced to bring them into phase can be used to determine the angle between the direction of wave source and a line of the receivers.

With the use of two receiving elements two separate translating devices may be used, particularly if the translating devices are employed with additional interpretation, for example in the case of the use of telephone receivers as translating devices. With two telephone receivers as translating devices one may be applied to each ear. With such an arrangement if one of the telephone receivers be stimulated in advance of the other the sound will appear to come from the side on which is the advance receiver. By introducing retardation into the line communicating with the advance receiver the sound produced by it may be retarded by such an amount that it will be in phase with the sound at the other ear. Under these conditions the sound will be physiologically located in a median plane through the head of the observer, or is said to be binaurally centered. The physiological perception of binaural centering is found by experience to be accurate and refined.

The direction of a source of energy, particularly a source of sound, can be determined with greater definiteness and discrimination by the use of a large number of receiving devices in proper geometric arrangement. A simple and efficient arrangement consists in placing the several receivers equally spaced in a straight line. Sound coming from any particular direction will strike these several receivers in succession so that the impulses in each receiver will have a fixed time interval behind the impulses in the adjoining receiver nearer to the source of sound. The amount of this time interval will depend upon the angle between the common base line of the receivers and the line along which the sound is traveling. The determination of this

- direction is made by finding the amount of time lag that must be introduced into the several receiver systems and their connections, in order to make the disturbances in 5 the receivers arrive simultaneously at one or more translating devices. More definitely, each of the receivers is connected through a system of electric circuits to a translating device, and electric retardation is introduced 10 into the several systems of electric circuits so as to make the currents additive in the translating device and thereby get a maximum response. As an alternative method, what may be called the forward half of the receiving line has its receiving elements severally connected through electric circuits to a translating device, such as a telephone receiver, applied to one ear, while the other half, which may be called the rear half of 15 the receiving line, has its receiving elements connected through electric circuits to a translating device, such as a telephone receiver, applied to the other ear. By adjusting the time retardations of the transmitting circuits 20 the receiver at each ear may be made to have maximum response, and the responses of the two receivers may at the same time be brought into such a phase relation that the sound will be binaurally centered. This latter combination 25 determines direction by a reading of a calibration corresponding to the adjustments of the retarding elements; said adjustment being characterized by simultaneous maximum and binaural centering. The operation 30 in this case is equivalent to focusing the line upon the source of sound and results in an elimination or suppression of disturbing sounds from sources having different angular bearings.
- 35 40 In the drawings the invention is illustrated as embodied in apparatus for determining the direction of sound waves and more particularly for determining the direction of submarine sounds. It is to be understood, 45 however, that the invention is not limited to this type of apparatus but may be embodied in apparatus for the direction detection of other forms of radiant or wave energy, such for example as electric waves.
- 50 55 Referring to the illustrated embodiment of the invention and particularly to Fig. 1, two receivers of the microphone type are indicated by reference numerals 1 and 2. These receivers are spaced apart a predetermined distance. For submarine sound detection receivers are spaced apart usually about five or six feet. The microphones 1 and 2 are supplied by a common battery 3. The microphone 1 is connected through the primary 4, of a transformer 5, and the microphone 2 is connected through the primary 6, of a similar transformer 7. The secondary 8, of the transformer 5, is connected through a retardation line consisting of inductance elements 9, 10 and 11 in series, and capacity elements 12, 13 and 14 in shunt, to a translating device 15, which is usually the ordinary magnetic telephone receiver, which is applied to one, say the left, ear of the observer. Similarly the secondary 16, of the transformer 7, is connected through a retardation line comprising inductance elements 17, 18 and 19 in series and capacity elements 20, 21, and 22 in shunt, to the right hand receiver 23, of the telephone head piece. For convenience an inductance such as 9, with its adjacent condenser 12, may be designated a section of the line. Instead of connecting the condenser of a section to the terminal of the inductance of the same section, it may be connected to the center of said inductance, as illustrated in Fig. 2.
- 55 60 The several sections are computed to each introduce a certain time lag into the current traversing them from the transformer secondary to the translating device, and the time lag introduced into the line by one of the sections may be designated as t . In practice in submarine reception of sound it has been found convenient to make t equal to about .000065 seconds. This is approximately the time required for sound to travel four inches in water.
- 65 70 Let the microphone receivers 1 and 2, be four feet apart. Suppose a sound strikes the receivers coming from a direction at right angles to the base line joining them. The two receivers will be excited simultaneously and if the lines to the respective translating ear pieces 15 and 23, have the same number of sections, the sound will be binaurally centered. Suppose, however, that the sound is traveling in a line in the direction of the base line joining the microphones and strikes the receiver 1, first. It will strike the receiver 2, later by the time required for the sound to travel four feet in water. If two lines to the head piece have the same number of retarding sections in them, the sound will be binaurally located in the receiver 15, which we have supposed applied to the left ear. However, if an excess of twelve retarding sections, each equivalent to four inches in water, are interposed in the line between the transformer 5, and the ear piece 15, the sounds in the two ear pieces will occur simultaneously and the sound will be binaurally centered. For any direction intermediate between the end-on direction and the perpendicular direction the time required to travel from the first receiver to the second will be intermediate between the time to travel four feet in water and zero time, so that a number of sections intermediate between twelve and zero will have to be interposed as excess in the line between 8 and 15. In practice these elements are introduced from one ear system to the other by means of a switching device that may be calibrated directly in terms of the angular bearing of the 130

disc 85, as shown in Fig. 4, capable of rotation and provided on its upper face with a calibrated angular scale which may be read through the window 86. The slip rings, 82 and 83, are carried on the stationary bottom plate 87, of insulating material in position to have sliding contact with the brushes, 80 and 81, which are carried by the rotatable disc 85, and are connected with the blocks, 65 and 66, respectively.

As shown in Fig. 3, the retardation line of the compensator is divided into twenty-three sections numbered 90 to 112, respectively. Each section includes an inductance 42, and a capacity 43. The capacities 43, are connected in multiple to a common connection 113, going to line 114, which joins the middle point between the receivers 33 and 34, to one side of the transformers 35 and 36. The ends 20 of the inductance of 42, are connected to the inner and outer brushes 120 and 121, of adjacent pairs of brushes. As shown in Figs. 3 and 4, the inner and outer brushes 120 and 121, are arranged in pairs arranged in two concentric circles under the series of rotating blocks. For convenience these pairs of brushes are designated by reference numbers 130 to 153 inclusive. As shown in Fig. 4, the series of pairs of brushes 120 and 121, are carried upon 30 insulating mountings on the stationary bottom plate 87.

If the rotatable series of blocks has the position shown in Fig. 3, the current from the secondary of the transformer 35 goes through the lead line 160 to the outer brush 121 of the pair of brushes numbered 130, then across the conducting block in contact with this pair to the inner brush 120 and to the inductance 42 of section 90, then across the pair of brushes 131 through the inductance 42, of section 91, and so on through sections 92 to 100 inclusive to the outer brush 121 of the pair of brushes numbered 141. This brush bears against the L-shaped block 65. The current passes through the block 65 to the brush 80 and slip ring 82 to the ear piece 33 of the telephone receiver and through the connection 114 back to the transformer secondary. Similarly the current from the secondary of the transformer 36 goes through the lead 161 to the outer brush 121 of the pair of brushes numbered 153, across the conducting block to the inner brush 120 of this pair, then through the inductance 42 of the section of the line numbered 112 and so on through the sections of the line 111 to 102 inclusive, to the inner brush 120 of the pair of brushes numbered 142. This brush bears on the L-shaped block 66. The current passes through the block 66 and its brush 81 to the slip ring 83, to the ear piece 34 of the telephone receiver set, and through the common connection 114 to the transformer secondary.

In this position of the parts there are eleven 65 sections of the retarding line of the compen-

sator in series with the secondary of each transformer and the compensator will binaurally center a sound coming at right angles to the base line joining the microphone receivers 31 and 32. If the sound comes at an oblique angle and reaches the receiver 31 first, the handle 165 of the compensator is turned to rotate the plate 85 with its series of conducting blocks and introduce more sections in series with the secondary of the transformer 75 35 and the head piece receiver 33, and subtract sections from the portion of the line in series with the secondary of the transformer 36 and receiver 34. The handle is turned until the sound is binaurally centered in the ears of 80 the observer. When so set the excess of compensator sections in series with the secondary of the transformer 35, retards the current so that the sound in the two receivers is in phase. The base line between the microphonic receivers 31 and 32 is known. The time retardation caused by each section of the compensator line is known, being calculated from its electric constants and the angular scale 85 is calibrated in degrees from such computation. The observer can determine the angle 90 of incidence between the sound and the base line of the microphonic receivers 31 and 32 by reading the scale.

The computation of the proper constants 95 of the retardation line used in the electric compensator is as follows:

If

R =resistance per section of the line

C =capacity per section of the line

L =inductance per section of the line

the current after traversing n sections of the line will have the value $I_n = I_o e^{-na}$. Where I_o =the input current, I_n =the current traversing the n th section of the line. The quantity a in the exponent is called the attenuation constant per section of the line.

The current after traversing n units of the line will lag behind the input current by an amount nt , where t is the time retardation per section of the line. (For a similar equation see page 294, "Electric oscillations and electric waves," by applicant, published 1920 by McGraw-Hill Book Co., and for the derivation of further equations set forth in this specification see Chapter XVI of said book, especially pages 294, 296 (Sec. 264), 305, 314, 315.

If $\sqrt{LC}$ be sufficiently small in comparison with the period of all significant audible frequencies, a mathematical investigation shows that

$$(1) \quad t = \sqrt{LC}.$$

Another significant relation in connection with the line is that, in order to avoid reflections at the terminal apparatus (translating device, and in this case the telephone receivers) the impedance Z of the translating 125

source of the sound from the base line joining the receiving microphones. When the direction of the sound is determined by introducing variable amounts of time lag into the circuits from the microphones to the telephone head piece, the process is known as variable compensation. This permits the microphones to be fixed in position. The direction may, however, be determined by what is known as fixed compensation. If, for example, the microphones 1 and 2, are connected to the respective ears through electric lines having the same time retardation, then the sound may be binaurally centered by revolving the microphone system until the sound is binaurally centered at which point the sound will be at right angles to the base line adjoining the microphones. Or, the circuit to one microphone may be given a time retardation equal to the time to travel from one microphone to the other, in a direct line. In this case the sound may be binaurally centered by revolving the line of the microphones until it points toward the sound, the microphone having the excess time lag introduced into its connections, being nearest the sound.

Returning to the matter of variable compensation, Fig. 2 is a development of the switch mechanism for varying the compensation by introducing excess of compensating elements into the telephone receiver responsive to the one or the other of the microphone receivers.

Referring to Fig. 2, reference numerals 31 and 32 indicate two microphones suitably spaced apart, and 33 and 34 the two receivers of a telephone head piece respectively responsive to microphones 31 and 32. 35 and 36 are two transformers, called input transformers, by means of which electromotive forces produced by the periodic microphone currents are impressed upon the two ends of the compensator. The compensator is illustrated as having five elements, numbered from 37 to 41 inclusive, each element comprising an inductance 42, and capacity, 43. A number of stationary brushes are arranged in pairs and indicated by reference numerals 44 to 55 inclusive. A series of movable conducting blocks, 56 to 75 inclusive, is arranged to be moved along under and bridge the stationary brushes. The end blocks, 56 to 64 and 67 to 75 inclusive, are all alike and are arranged to bridge across between the two brushes of a pair. The blocks, 65 and 66, are L-shaped as shown in the drawing, and are respectively connected to the telephone head piece receivers, 33 and 34. These L-shaped blocks divide the system of circuits in such a way that the current from the transformer 35, goes through the telephone receiver 33, and the current from the transformer 36, goes through the telephone receiver 34, independently, since the connection 76, from the common point of the

two telephone receivers to the common point of the two transformer secondaries has negligible resistance. In the position shown in the figure the current through the secondary of the transformer 35, and the telephone receiver 33, goes through two sections, 37 and 38, of the compensator line, the section 39, having its inductance short circuited by the block 65, while the current from the transformer 36 to the telephone receiver 34, goes through one section of the compensator line, the section 40, having its inductance short circuited by the block 66. If now the system of blocks is moved to the left by an amount equal to the distance between the centers of two adjacent blocks, the short circuit on the coil of section 40, is opened so that the current on this side now passes through two sections, 40 and 41, of the compensator. This movement does not change the number of sections of the compensator in series with receiver 33. By examination, it is seen that a movement to the left of the system of blocks by another step equal to the distance between the centers of the two adjacent blocks will short circuit the inductance of section 38, leaving only one section of the line in series with telephone receiver 33; while the effect of this motion does not change the number of sections in series with telephone receiver 34. This operation carried on successively results in changes amounting to an increase of the excess of elements to one of the telephone receivers by an amount equal to one section for each step in the translation of the blocks. It is to be noticed that this operation nowhere results in an interruption or significant variation of the amplitude of the current to the two telephone receivers.

By this step-by-step movement to the blocks all of the sections of the line may be put in series with the telephone receiver 33, or with the telephone receiver 34, or part in series with one telephone receiver and part in series with the other.

In practice the number of sections in the compensator line is usually greater than that shown schematically in Fig. 2, and the movable blocks are mounted, insulated from one another, upon a rotating disc. The switch, as constructed for two microphones, is shown diagrammatically in Fig. 3. Reference numerals 33 and 34 indicate the two receivers of a telephone head piece, respectively responsive to microphones 31 and 32, being connected through the transformers 35 and 36, in the same way as shown in Fig. 2. The blocks, 65 and 66, are connected respectively to the telephone receivers, 33 and 34, through the brushes, 80 and 81, and the slip rings, 82 and 83, respectively. These correspond to blocks 65 and 66 of Fig. 2. The blocks 56 to 64 and 67 to 75 inclusive, correspond to similarly numbered blocks on Fig. 2. The blocks are mounted on an insulating

device shall satisfy approximately the equation

$$(2) \quad Z = \sqrt{\frac{L}{C}}$$

Another relation is that the attenuation a of a section of the line is

$$(3) \quad a = \frac{R}{2} \sqrt{\frac{C}{L}}$$

There follows a numerical calculation of sections proper to form a retardation line for use in an electric compensator for significant audible sound frequencies. Let it be supposed that it is desired to make the time retardation per section of the line have the value $t = 6.5 \times 10^{-5}$ seconds; then

$$(4) \quad \sqrt{LC} = 6.5 \times 10^{-5} \text{ seconds by equation (1).}$$

Suppose that the translating device has an impedance of say 260 ohms. Then by equation (2) we have

$$(5) \quad \sqrt{\frac{L}{C}} = 260 \text{ ohms.}$$

Taking the product of (5) and (4) we obtain

$$(6) \quad L = .0169 \text{ henry.}$$

Taking the quotient of (4) and (5) we obtain

$$(7) \quad C = .25 \times 10^{-6} \text{ farads} = .25 \text{ microfarads.}$$

The values given in equations (6) and (7) are the required values of inductance and capacity for an electric compensator for the given conditions.

Let us next investigate the attenuation introduced by thirty units of such a line. This will depend on the resistance of the wire employed. If the coils have each a resistance of $R = 9$ ohms, we have by (3) $a = \frac{R}{2} \sqrt{\frac{C}{L}}$

whence

(8) $a = 9/520$, which substituted in the equation for I_n in terms of I_0 gives

$$(9) \quad I_{30} = .6 \times I_0,$$

where I_{30} is the current in the 30th section of the line.

These results show the method of obtaining proper constants for the required retardation per section of the line and show also, incidentally, how much the current will be reduced in intensity by the action of the line.

The example is only illustrative and it is easy to obtain much less resistance in the coils than the 9 ohms given in the example, and therefore possible to obtain less attenuation than that specified, while preserving the proper retardation per section of the line.

There is one other consideration in the design of the retardation line; namely, it is important to have the retardation substantially independent of the frequencies that occur in the source of sound, so that the

sound which arrives at the ear will not be modified in quality by the operation of the line. This result is attained most perfectly by making the time retardation per section of the line small, so that the retardation time per section of the line, smaller than that here specified, may be employed. On the other hand if the retardation per section is made too small, the number of sections required in a practical case may become too large for easy construction. The value of the time retardation per section chosen in the example is sufficiently large to permit of an economical construction and is sufficiently small to have the line transmit all frequencies less than about four thousand cycles per second, and therefore permits transmission of sounds of significant audible frequencies.

Fig. 5 shows a wiring diagram of an electric compensator for use with two rows of microphones, twelve microphones in each row, and Fig. 6 shows the assembly of the several switches and their connections which are indicated diagrammatically in Fig. 5.

Referring to Fig. 5, reference numerals 201 to 212 indicate terminals which are connected to twelve microphones placed in a row, for example, on the port side of a ship's hull, and reference numerals 301 to 312 indicate terminals which are connected to a similar row of twelve microphones, placed for example on the starboard side of a ship's hull. All of these microphones have their other terminals connected in parallel to a common connection, as shown, which is connected at the binding post 213 of one side of the battery 214. The other side of the battery 214 is connected through a switch 215 to a common lead 216 from which electric currents pass through the primary coils P of twenty-four transformers numbered 217 to 228 and 317 to 328 inclusive. The secondaries of these transformers are marked S, of which there are two classes to be referred to, as starboard secondaries and port secondaries, being the secondaries of the starboard transformers 217 and 228 and of the port transformers 317 to 328 respectively. By means of a multiple point double throw switch, the blades of which are indicated at B, either the starboard secondaries or the port secondaries can be connected to the input terminals of the compensator which are formed by the leads 401 to 412 inclusive. The other sides of the transformer secondaries are connected to a common lead 413.

When the switch blades B are all thrown to the right in Fig. 5, the secondary of the transformer 217 is connected to one end of a retardation line 501 of seven sections. The secondary of the transformer 219 is connected to the other end of this retardation line. At the several sections of this retardation line are switch contact blocks numbered 511 over which a brush 521, is movable. This brush is

carried on a ring 531. The electric currents from the secondaries of the transformers 217 and 219 pass into the two ends of the retardation line 501 and out through the brush 521 to the ring 531. Current from a secondary of the intermediate transformer 218 passes through the fixed retardation line of three elements 502, directly to the ring 531. By this process currents from the secondaries of the first three transformers 217, 218 and 219 of the series are led to the common point 531. By moving the brush 521 the time retardation of the current from the transformer 217 may be made less than that from the transformer 218, while retardation of the current from the transformer 219 is made greater than that from 218 by an equal amount; so that if the secondaries of the transformers 217, 218, 219 are actuated by three microphones equally spaced, currents which are out of phase in the microphones may be brought into phase at the ring 531. In a similar manner the currents in the secondaries of the transformers 220, 221 and 222 are brought together at the ring 532, in phase with each other, but not necessarily in phase with the current at 531. In like manner the rings 533 and 534 collect currents from the remaining two groups of three microphones each. The condensers 541, which are connected to the inductances 542, of the eight retardation lines 501 to 508 inclusive have their opposite terminals connected in multiple to the common return lead 413.

It is now necessary to have the manipulation of such a character that the currents in the several rings 531, 532, 533 and 534 may be further united. This is partially done by means of two retardation lines 601 and 602 each of which consists of inductances 642 in series and capacities 641 in shunt. The currents from the rings 531 and 532 pass to brushes 551 and 552 respectively which are connected by the leads 661 and 662 respectively to the two ends of the retardation line 601. The several sections of this retardation line have contact blocks 611 (not shown in Fig. 5) over which pass a brush 621 connected to the ring 631. By a proper adjustment of the brush 621 along the blocks 611, the currents which in general were out of phase in the rings 531 and 532 are brought into phase at the ring 631. In like manner the currents from the rings 533 and 534 pass through the retardation line 602 and are brought into phase at the ring 632. The rings 631 and 632 are connected by brushes 651 and 652 to leads 761 and 762 respectively which are connected with two L-shaped blocks 711 and 712 of the series of movable blocks of the retardation line 701. The currents entering these blocks 711 and 712 respectively are in general still out of phase, and must be still further retarded with reference one to the other, and this is done in the retardation line 701 of inductances 742 in series and capacities 741 in shunt. This line consists of twenty three sections, with each section connected with the upper and lower brushes 721 and 722 respectively of two adjacent pairs of brushes, as shown in the diagram. The connections are so made that the rectangular blocks 713 of the series of movable blocks bridge the brushes of each pair in such a manner that the inductance coils 742 of the sections are connected in series respectively on each side of the two L-shaped blocks 711 and 712. The blocks 711 and 712 interrupt the series connection so that the currents flowing into these blocks pass independently one from the block 711 to the left along the retardation line and out through the lead 801 to the telephone receiver 803; while the current entering the block 712 passes out to the right along the retardation line and through the lead 802 to the telephone receiver 804. These currents which pass through the two telephone receivers then unite in the common lead 805 communicating with the lead 413, and thence to the common junction of all the secondaries of the transformers 217 and 228 inclusive. By the proper adjustment of the movable blocks, time retardation is introduced into the current through one of the telephone receivers 803 or 804 in excess of the retardation in the current through the other telephone receiver so as to bring these currents into phase, and to effect a proper binaural centering. The currents from the six transformers 217 to 222 have been brought into phase at the ring 631 by the retardation lines 501, 503, 504, and 601 so that the sound in the left hand telephone receiver is a maximum independently of the retardation line 701. Similarly the currents from the six transformers 223 to 228 have been brought into phase at the ring 632. The function of the line 701 with the connections from its two ends to the telephone receivers separately is to bring the two maximum sounds in the two receivers into phase so as to cause the physiological sense of the binaural centering of the sound.

The retardation line 701 may however be used to combine the currents so as to produce a maximum sound in each telephone receiver but without the binaural sensation. To use the compensator as a pure maximum instrument without the binaural, the switch 810 is closed in the circuit 811. This connects the two telephone receivers in multiple to the common junction point of the leads 801 and 802 from the two ends of the line 701. The listener will get no binaural sensation but if the contact blocks of the line 701 are properly positioned to bring the currents from the rings 631 and 632 into phase with each other, the listener will get a maximum sound in the telephone receivers.

It is to be noted that the same position of the contact blocks of the line 701 which gives

binaural centering when the switch 810 is open, gives a maximum when this switch is closed. The binaural and the maximum may therefore be used to check each other, by simply closing and opening the switch 810.

While the binaural setting of the compensator is usually employed in determining the direction of submarine sounds such as that of a ships' propeller, the setting by means of the maximum may be employed where the sound is of such a character that binaural centering is difficult, as for example on a sound source emitting a purr sound or sustained musical note.

If the compensator is designed to be a maximum instrument with no binaural setting, the final retardation line 701 can be made much simpler than that shown in the drawing because the retardation line 701 as shown is designed particularly for binaural direction determination. If a maximum alone is to be had, the line 701 may be replaced by a line of the type shown at 601, 602 and the leads 761, 762 connected to the ends of such a simple line and a simple brush connected with a single receiver would be arranged to make contact at the points between the sections of the line, substantially in the same manner as the brush 621 makes contact with the contact blocks of the line 601.

In Figure 6 is illustrated diagrammatically the arrangement of the several switches for the retardation lines. The switches are operated from a common shaft 900, which is shown broken for purposes of illustration.

Corresponding parts on Figs. 5 and 6 are indicated by the same reference numerals. The fixed retardation lines 502, 504, 506, and 508, are indicated at the bottom of Figure 6. The variable retardation lines 501, 503, 505 and 507 are shown as surrounding the lower four switch plates. The small arrow heads 905 on the leads indicate that they are continued around behind the switch plates. The brushes 521, 522, 523, 524 are carried by the rotatable rings 531, 532, 533, 534 respectively and move over the contact blocks 511, 512, 513, 514 respectively. The brushes 551, 552, 553, 554 are connected through the leads 661, 662, 663, 664 respectively to the opposite ends of the respective retardation lines 601 and 602. The common return lead is indicated at 413 corresponding to the same numbered lead on Figure 5.

The construction of the switches for the two retardation lines 601 and 602 is similar to the four lower switches, except that there are eleven instead of seven contact blocks.

The switch for the line preferably used with 701 is shown at the top. The general structure of this switch is the same as the switch shown in Figures 3 and 4. The series of contact blocks 711, 712 and 713 are carried on the underside of a rotatable disc 770. The slip ring 782 and 783 are also carried on the

bottom of this disc and make contact with brushes 780 and 781, which are connected with L-shaped blocks 711 and 712. The leads 761 and 762 are connected to the slip rings 782 and 783. Except that these slip rings and brushes are not shown in Figure 5, the connections in Figure 5 are the same as in Figure 6.

The general arrangement of parts of this switch is the same as that shown in Figure 3 and Figure 4, except that the electric currents are lead into the retardation line through the L-shaped switch blocks and the telephones are connected to the ends of the line, whereas in the switch shown in Figures 3 and 4, the currents are led into the ends of the line and the telephone receivers are connected to the L-shaped blocks. These two methods of connection are equivalent.

The disc 770 is provided with a scale, not shown, similar to the disc 85, in Figure 4. This scale is calibrated in angles so that when the observer makes a setting either by means of the binaural or the maximum, he can read directly the angle of incidence of the sound with respect to the base line of the row of microphones.

The shaft 900 connects the switches for the several retardation lines together so that the blocks and brushes for the several lines move in unison and in proper angular relation to each other.

Let the eight retardation lines 501, 502, 503, 504, 505, 506, 507 and 508 connected to the secondaries of the transformers be designed as lines of class I. Let the two retardation lines 601 and 603, be called lines of class II. Let the retardation line 701, be called a line of class III. Let L_1 and C_1 be the inductance and capacity of each section of the lines of class I. Let L_2 and C_2 be the inductance and capacity of each section of the lines of class II. Let L_3 and C_3 be the inductance and capacity of each section of the line of class III.

In order to minimize reflections at the junction points of the lines of the several classes, certain relations must be approximately fulfilled.

The current is fed to one end of the retardation line 601 through the lead 661, through three retardation branch lines, one branch being through the fixed retardation line 522 and the other branches being the two parts of the retardation line 501, at the two sides of the contact point 521, respectively. Similarly the other ends of the retardation lines 601 and 602, which are of class II, are each fed by three retardation branch lines of class I. To minimize reflection the relation between the inductance and capacity of the lines should be:

$$(10) \quad \sqrt{\frac{L_1}{C_1}} = 3 \sqrt{\frac{L_2}{C_2}}$$

Similarly the current flowing through the

left hand side of the retardation lines 701 from the block 711 is formed by the uniting of the currents flowing through the two halves or branches of the retardation line 601 to the 5 take-off brush 621. The currents in the two halves of the other retardation line 602, of class II, similarly unite at the contact brush 622 and flow to the right from the block 712 along the retardation line 701 of class III. 10 To avoid reflection at the connection between the retardation lines of class II and class III, the relation should be

$$(11) \quad \sqrt{\frac{L_2}{C_2}} = 2 \sqrt{\frac{L_3}{C_3}}$$

These equations are the conditions requisite for a maximum transmission of current to a line where the currents in the tributary branches are in phase with each other. For 20 a maximum input of current to each of the lines of class I and to minimize electrical reflections at the input terminals of these lines, the following relation should also be approximately fulfilled.

$$(12) \quad \sqrt{\frac{L_1}{C_1}} = Z_o$$

where Z_o = the impedance of the input apparatus (in this case the impedance of a microphone with its transformers, etc.).

To minimize reflections at the output apparatus or translating device (in this case the telephone receiver) connected to a line of class III, the following relation should be approximately fulfilled.

$$(13) \quad \sqrt{\frac{L_3}{C_3}} = Z_t$$

where Z_t = impedance of the translating device fed by a single branch of the line of class III, (in the present case one of the telephone receivers).

In addition to these relations let the time retardation per second of the lines of classes I, II and III be respectively t_1 , t_2 , t_3 , then

$$(14) \quad \begin{aligned} t_1 &= \sqrt{L_1 C_1} \\ t_2 &= \sqrt{L_2 C_2} \\ t_3 &= \sqrt{L_3 C_3} \end{aligned}$$

By combining the several equations we obtain

$$(15) \quad \begin{aligned} L_1 &= Z_o t_1 \\ L_2 &= \frac{Z_o t_2}{3} \\ L_3 &= \frac{Z_o t_3}{6} \end{aligned}$$

$$(16) \quad \begin{aligned} C_1 &= \frac{t_1}{Z_o} \\ C_2 &= 3 \frac{t_2}{Z_o} \\ C_3 &= 6 \frac{t_3}{Z_o} \end{aligned}$$

When t_1 , t_2 , t_3 , and Z_o are given, L_1 , L_2 , 65 L_3 and C_1 , C_2 , C_3 can be calculated.

For example let $t_1 = t_2 = t_3 = 6.5 \times 10^{-5}$ seconds and let $Z_o = 195$ ohms, then

$$(17) \quad \begin{aligned} L_1 &= .0127 \text{ henry} \\ L_2 &= .0042 \text{ henry} \\ L_3 &= .0021 \text{ henry} \end{aligned}$$

$$(18) \quad \begin{aligned} C_1 &= \frac{1}{3} \times 10^{-6} \text{ farads} \\ C_2 &= 1 \times 10^{-6} \text{ farads} \\ C_3 &= 2 \times 10^{-6} \text{ farads} \end{aligned}$$

Similarly the impedance of the translating device to avoid reflection can be calculated. In the case given above each of the telephone receivers should have an impedance Z_t , given by the equation.

$$(19) \quad Z_t = \frac{L_3}{C_3} = 35 \text{ ohms}$$

While preferred embodiment of the present invention has been illustrated and described with particular reference to compensation for the determination of the direction of sounds, it is to be understood that the invention is not limited to its preferred embodiment or to its adaptation to sound waves, but may be embodied in other structures adapted for other uses within the scope of the following claims:

I claim:

1. A combination with an electric line formed in a plurality of sections, of a switch comprising two rows of brushes arranged in opposing pairs, and connections from each brush of a pair to the ends of two adjacent sections of the line, and a plurality of blocks disposed in a row and relatively movable along the rows of brushes, two adjacent blocks being shaped, one to extend across two adjacent brushes of one row and the other across two adjacent brushes of the other row so that each block is always in contact with a brush of the respective rows, these two blocks being spaced so as to leave an interruption in the line between, and blocks arranged in a series at each side of these two blocks for bridging across opposing brushes and maintaining the sections of the line in series at either side of the first two blocks, substantially as described.

2. An electric compensator comprising a series of retardation branch lines and a retardation line common to all of said branch lines and connected thereto, each of said lines comprising inductances in series and capacities in shunt and arranged in sections, the ratio of the inductance to the capacity per section of each of the branch lines being n^2 times the corresponding ratio for the sections of the retardation line common to said branch lines as described.

3. An electric compensator adapted for use with receivers of wave energy in which electric currents are produced, comprising two auditory translating devices, one for each ear, means for transmitting the currents from a plurality of receivers to one translating device including electric re-

tardation lines for bringing the currents into phase and causing a sound maximum and for transmitting the currents from others of the receivers to the other translating device 5 including electric retardation lines for bringing the currents into phase and causing a sound maximum, and a retardation line for bringing the currents in the two translating devices into phase with each other for a 10 binaural setting, substantially as described.

4. A compensator adapted for use with a plurality of electric receivers of wave energy comprising two auditory translating devices, one for each ear, and means for transmitting 15 the wave energy from the receivers to the auditory devices, including electric retardation lines for producing a maximum combined with a binaural at the translating devices, substantially as described. 20 5. A system for the reception of wave energy comprising a plurality of groups of receivers, each group being made up of at least two receiver units spaced in a definite configuration, means associated with said receivers for translating said wave energy into electric currents, means comprising tributary retardation lines associated with said translating means for making the currents in the group additive in phase, an indicating means, and means for associating the group currents, including a main retardation line 25 for bringing said group currents in phase at said indicating means and means for varying the amount of retardation of said retardation lines. 30 6. A system for the reception of sound

energy comprising a plurality of groups of sound receivers, each group being made up of at least two sound receiver units spaced in a definite configuration, means associated with said sound receivers for translating said sound energy into electric currents, means comprising tributary retardation lines associated with said translating means for making the currents in the group additive in phase, an indicating means, and means for associating the group currents, including a main retardation line for bringing said group currents in phase at said indicating means and means for varying the amount of retardation of said retardation lines. 40 45 50

7. A system for determining the direction of a source of sound energy comprising a plurality of groups of sound receivers, each group being made up of at least two sound receiver units spaced in a definite configuration, means associated with said sound receivers for translating said sound energy into electric currents, means comprising tributary retardation lines associated with said translating means for making the currents in the group additive in phase, an indicating means, and means for associating the group currents, including a main retardation line 55 for bringing said group currents in phase at said indicating means and means for varying the amount of retardation of said retardation lines, and means indicating, at the time said currents are in phase, the direction 60 of the sound source. 65

GEORGE W. PIERCE.
